a corporation of New York

Application March 26, 1946, Serial No. 127,971

Term of patent 14 years

(Cl. D61—1)

To all whom it may concern:

Be it known that I, John R. Carpenter, a citizen of the United States, residing at 15 West 29th Street, New York, in the county of New York and State of New York, have invented a new, original, and ornamental Design for a Portable Developing Tank, of which the following is a specification, reference being had to the accompanying drawing, forming part thereof, in which—

Figure 1 is a top plan view of a portable developing tank, showing my new design;

Figure 2 is a side elevational view of the portable developing tank shown in Figure 1;

Figure 3 is an end elevational view of the portable developing tank shown in Figure 1; and

Figure 4 is a perspective view of the portable developing tank shown in Figure 1.

What I claim is:
The ornamental design for a portable developing tank, as shown.

JOHN R. CARPENTER.
